UNITED STATES PATENT OFFICE.

ALBERT E. BOOKWALTER, OF COEUR D'ALENE, IDAHO.

ORE SEPARATOR.

Application filed September 7, 1922. Serial No. 586,699.

To all whom it may concern:

Be it known that I, ALBERT E. BOOKWALTER, a citizen of the United States, residing at Coeur d'Alene, in the county of Kootenai and State of Idaho, have invented certain new and useful Improvements in Ore Separators; and I do declare the following to be a full, clear, and exact description of the invention, such as will enable others skilled in the art to which it appertains to make and use the same.

My invention relates to improvements in ore washing machines of the type employing a reciprocating frame movable within a water box above a series of cells and the principal object is to improve upon the construction shown in my U. S. Patent 1237237 of August 14, 1917, by providing a plurality of vertically movable plungers between the sides of the water box and the reciprocating separating frame, whereby to produce vertical pulsation of the water through the frame simultaneously with the horizontal reciprocation of said frame, it having been found that these combined movements produce much more effective separation of the ore from the gang.

A further object is to provide a novel association of parts for collecting fine particles of ore within the separating frame and discharging this ore into the subjacent cell, each time a pulsation of water moves upwardly through the bottom of the separating frame.

A still further aim is to provide a separating arrangement in which wool may be effectively used for collecting extremely fine particles of ore which would otherwise be lost.

Another object is to provide a novel bumper which is struck by the reciprocating separating frame, each time the latter strokes in one direction, whereby to hasten the passage of the material through the separating frame and causing more effective agitation than can otherwise be obtained.

With the foregoing in view, the invention resides in the novel subject matter herein-after described and claimed, the description being supplemented by the accompanying drawings.

Figure 1 is a top plan view with the supporting frame in horizontal section.

Figure 2 is a central vertical longitudinal section as indicated by line 2—2 of Fig. 1. 55

Figure 3 is a side elevation with parts in section on line 3—3 of Fig. 1.

Figure 4 is a vertical transverse section on line 4—4 of Fig. 1.

Figure 5 is a detail sectional view through 60 the bottom of the separating frame.

Figure 6 is a view similar to Fig. 5 but showing a different form of construction.

In the drawings above briefly described, the numeral 1 designates a water box of any 65 suitable construction, the ends 2 of said box being of considerably less height than the sides 3 thereof. The box is divided by one or more transverse partitions such as that indicated by the numeral 5, into a plurality 70 of cells 4 in which the precious metal is collected and from which it may be removed in any appropriate manner.

Mounted in the box 1 above the ends 2 and partitions 5 and spaced above the sides 3 of said box, is an ore shaking frame 6, said frame comprising parallel sides 7, ends 8, and a partition 9, said ends and partition being disposed above the corresponding parts of the box 1. The ends 8 and partition 9 are 80 all formed with horizontal slots 10, the end-most of which communicate with an inlet chute 11 and a discharge chute 12. The slot 10 of the partition 9 serves to permit the passage of material from one half of the frame 6 into the other half thereof, both halves having therein means for so acting upon the ore laden slime as to separate the ore therefrom.

While frame 6 may be mounted in any 90 suitable manner for horizontal reciprocation, it is preferably suspended upon hang-ers 13 from the main frame structure of the machine. Similarly, any appropriate means may be devised for reciprocating said frame 95 but I have shown an eccentric 14 on a trans-verse drive shaft 15, and a pitman 16, for this purpose.

Since the shaking frame 6 and parts carried thereby must operate in the water 100 while the box 1 stands stationary, it is nec-essary to provide for preventing the leak-

- age of water above the ends 2 and partition 5. For this purpose, end sheets 21 and a partition sheet 22 are provided, suitably secured in place. Water may be supplied to 5 the box 1 through suitable piping P and regardless of the water level, provided it is below the top of the frame 6, no leakage will take place between the box and frame, due to the sheets 21 and 22.
- 10 All of the features above described are shown in Patent 1237237 to which I have referred and they therefore constitute no parts of the present invention except in connection with the features of improvement 15 described below.

The numerals 23 designate a pair of transverse shafts mounted rotatably upon the main frame structure of the machine above the reciprocating frame 6, one of these 20 shafts being driven by the shaft 15 and a belt 24, while this shaft drives the other shaft 23 by means of another belt 25. The two shafts 23 carry eccentrics 26 adjacent thereon which shafts are preferably of the 25 adjustable throw types, said eccentrics being received in eccentric straps 27 on the upper ends of plunger rods 28 having horizontally elongated plungers 29 on their lower ends. These plungers are located at 30 opposite sides of the partition sheet 22 and are interposed between the sides 7 of the frame 6 and the side walls 3 of the tank 1. By this arrangement, it will be seen that as the frame 6 is horizontally reciprocated, 35 the plungers 29 will be vertically pulsated so that water from the tank is alternately moved upwardly and downwardly through the frame, thereby effecting a very thorough separation of the ore from the gang 40 and the like.

The frame 6, in the construction shown in Figs. 1-5, is provided with a bottom 30 having a plurality of openings 31, the lower end of each of these openings being provided 45 with an annular valve seat 32 which may well be formed from a piece of gas pipe. A ball valve 33 is positioned loosely within the opening 31 to engage the seat 32 and a layer of wool 34, preferably about two inches 50 thick, rests upon the bottom 30 and returns the ball 33 in place. The layer of wool is in turn held down by a retainer 35 of screen wire or other suitable material. This association of parts is very effective. While the 55 gang and the like pass freely over the screen 35, the precious metal permeates through the wool 34 and collects in the opening 31 around the balls 33, but each time an upward pulsation of water takes place, these 60 balls are elevated from their seats and a discharge of metal takes place into the cells 4, this pulsation of water also serving to rinse the metal loose which has been caught in the wool 34.

In addition to the features above described, the frame 6 is preferably provided with upper and lower sets of transversely inclined slats 36 and 37 positioned above and below the ore separating means, for performing well known agitating functions. 65 70

In the form of construction shown in Fig. 6, a sheet of wire 38 rests upon the slats 37 and a bottom 39 rests upon this wire, said bottom being provided with a plurality of openings filled with shot as indicated by 75 the numeral 40. A layer of wool 41 is preferably provided on the bottom 39 held in place by a suitable retainer 42. This construction is preferable when operating upon certain kinds of ores. 80

In order to more effectively agitate the material and hasten its separation and passage through the machine, I provide a bumper at one end of the machine adapted to be struck by the frame 6, each time the 85 latter strokes in one direction. This bumper as here shown, is in the form of a transverse horizontal bar 43 under the discharge chute 12 in position to be struck by one end 8 of the frame 6, said bar being 90 yieldably connected with the main frame by coil springs 44 and bolts 45.

As excellent results may be obtained from the details disclosed, they are preferably followed, but within the scope of the invention 95 as claimed, numerous minor changes may of course be made.

I claim:

1. An ore separator comprising a water box, a separating frame mounted for horizontal movement in said box with its lower side below the water level, the sides of said frame being spaced from the sides of the tank, vertically movable plungers between said tank and frame sides, and means for simultaneously shaking said frame horizontally and pulsating said plungers vertically. 100

2. An ore separator comprising a water box having end walls and a partition all of less height than its side walls, an elongated separating frame above said end walls and said partition and spaced inwardly from said side walls, flexible transverse sheets secured to said frame, said end walls, said partition and said side walls, and means for horizontally reciprocating said frame; together with plungers at opposite sides of said partition between said frame and said side walls, and means for vertically pulsating said plungers while reciprocating said 110 frame. 115

3. An ore separator comprising a water box, a separating frame mounted for horizontal movement in said box with its lower side below the water level, said frame having a bottom provided with a plurality of openings, check valves closing downwardly and controlling said openings, and means 125

for pulsating the water in the tank to force it upwardly through said openings.

4. An ore separator comprising a water box, a separating frame mounted for horizontal movement in said box with its lower side below the water level, said frame having a bottom provided with a plurality of

openings having annular valve seats, ball valves in said openings on said seats, and means for pulsating the water in the tank 10 to force it upwardly through said openings.

In testimony whereof I have hereunto affixed my signature.

ALBERT E. BOOKWALTER.
